UNITED STATES PATENT OFFICE.

CHAUNCEY M. GOODRICH, OF COTTAM, ONTARIO, CANADA.

BUILDING CONSTRUCTION.

1,418,297.

Specification of Letters Patent. Patented June 6, 1922.

Application filed July 17, 1920. Serial No. 396,963.

To all whom it may concern:

Be it known that I, CHAUNCEY M. GOODRICH, a citizen of the United States of America, residing at Cottam, in the Province of Ontario and Dominion of Canada, have invented certain new and useful Improvements in Building Construction, of which the following is a specification, reference being had therein to the accompanying drawings.

The invention relates to building constructions of the steel frame type and has for its object decreasing the obstruction due to columns for supporting successive floors without undue increase in the depth of the floor supporting girders.

In the present state of the art the successive stories of a steel frame construction are supported by aligned vertical columns, the spaces between said columns being bridged by laterally-extending beams or girders. The greater the length of the span between columns, the greater the depth required for the supporting girders or trusses, and consequently, the greater the amount of lost space vertically. On the other hand, if the spans between columns are reduced in length, the increased number of columns will increase the obstruction of the space between floors. Thus in the construction of storage garages the presence of columns interferes greatly with the freedom for moving the cars about, while increase in the depth of the girders and trusses will diminish the number of floors in the building.

My improvement consists essentially in a building construction in which the space between floors for one story is left unobstructed, while the space between floors of an adjacent story is utilized for the forming of a truss of the depth of said story. This truss may be formed by the regular floor-supporting girders of the two stories with intermediate vertical columns and braces and while the presence of these columns forms an obstruction, the amount of space occupied is comparatively small. Thus, if desired, alternate stories may be left comparatively free from columns without the necessity of any great increase in the depth of the beams or girders or in the appreciable loss of space in the intermediate stories.

My improved type of construction is applicable to buildings for various purposes,

but as specifically shown, is designed for a 55 garage, in which—

Figure 1 is a side elevation of the steel frame;

Figure 2 is a diagrammatic horizontal section on line 2—2;

Fig. 3 is a diagrammatic horizontal section on line 3—3 of Figure 1.

A are the vertical frame members on opposite sides of the building, and B are the horizontal or tie members extending between these vertical side members in the planes of the respective floors. Usually the members B are supported intermediate the sides of the building by a series of columns, which are arranged in alignment in successive 65 stories. With my improved construction the number of intermediate columns continuously in alignment is reduced and as shown a single column C is arranged centrally between the sides A. There are, however, intermediate vertical supports D which are arranged in alternate stories and these, in connection with the lateral members B, constitute a reinforcement. If desired, this reinforcement may be further strengthened 80 by diagonals E, as indicated on the right-hand side of the center of Figure 1.

As clearly shown in Figure 2, the space between floors in alternate stories is free and unobstructed, there being only the columns 85 C in the central lines and nothing intermediate to these and the side columns A. Thus, this space is particularly useful in a garage for convenience in moving about the vehicles. In the intermediate stories shown in 90 Figure 3 the space is more obstructed by the presence of the columns D, but is nevertheless available for storage, or in fact, for all uses for which the ordinary type of building construction is adapted. Thus without 95 injury to the usefulness of these intermediate stories, I have provided alternate stories which are free from obstruction.

What I claim as my invention is:

1. In a metallic frame building construction, the combination with a plurality of side and intermediate main columns, of horizontal girders extending between said columns to form a plurality of stories, and means located within the space comprising alternate stories for supporting the story above free from obstruction other than that of said main columns.

2. In a metallic frame building construction, the combination with a plurality of side and intermediate main columns, of laterally extending tie members forming a plurality of stories and intermediate supports between the floors comprising one story for supporting the story above free from intermediate supports.
3. In a metallic frame building construction, the combination with a plurality of side and intermediate main columns, of laterally extending floor girders forming a plurality of stories, means between the main side and intermediate columns in the space constituting one story for reinforcing said story and supporting the adjacent story above free from other obstruction than said main columns.
4. In a metallic frame building construction, the combination with side and intermediate main columns, of laterally extending members in the planes of the several stories and an arrangement of a greater number of columns in the space between floors constituting one story than between the space between floors constituting an adjacent story, the construction of said first mentioned story being such as to support said adjacent story free from obstruction other than said main columns.
5. In a metallic frame building construction, the combination with a plurality of side and intermediate columns, of a plurality of spaced pairs, of spaced floor girders connecting said main columns, the spaces between said spaced pairs of girders being obstructed only by said intermediate main columns and supporting means other than said intermediate main columns disposed between the girders of each pair of girders.
6. A building construction formed of a plurality of stories having means located within the space comprising alternate stories for supporting the adjacent story above free from obstruction.
7. A metallic frame building construction, comprising vertical columns and laterally extending tie members forming a plurality of stories, and means within the spaces comprising alternate stories to reinforce the same and support the adjacent story above free from obstruction.
8. A metallic frame building construction, comprising vertical columns and laterally extending tie members forming a plurality of stories and reinforcing members between the laterally extending tie members constituting the floors of alternate stories forming a brace to support the adjacent story above free from obstruction.

In testimony whereof I affix my signature.
CHAUNCEY M. GOODRICH.
